UNITED STATES PATENT OFFICE.

BERNHARD A. MOHR, OF NEW YORK, N. Y.

MACHINE FOR STRAIGHTENING AND GROOVING CANS.

Application filed July 30, 1926. Serial No. 125,972.

My invention relates to a machine for straightening buckled cans, and for forming grooves in cans to reinforce the cans against buckling. My machine is particularly adapted for the treatment of cans in which cakes of artificial ice are frozen, although it will be obvious that it could be used for other cans as well.

Cans used in ice-making plants are usually of rectangular cross-section, but taper slightly from a larger cross-section at the mouth to a smaller cross-section at the bottom, so that after the ice is formed, the can may be slightly warmed to free the ice cake from the can; after which the ice will slide out freely from the can. In service, however, the cans are soon battered and buckled to such an extent as to prevent the easy removal of the ice cake, and often considerable ice must be melted before the cake is small enough to slide past the unevennesses in the can. Not only does this result in considerable loss of ice, but much time and labor are wasted in the effort to get the cake out of the can. The cans are usually not square in cross-section, but the front and rear walls are much wider than the side walls. Buckling of the broader walls is not so serious a matter as the buckling of the narrower walls, probably because the broad walls are more flexible than the narrow side walls and hence will yield enough to permit the ice cake to slide out by gravity. Furthermore, it is the general practice to tip up the cans on one of the narrow sides, when sliding out the ice cake, hence any unevenness in the narrow sides will more surely prevent sliding of the ice cake out of the can.

It is an object of my invention, therefore, to provide a machine which is particularly adapted for straightening the narrow side walls of an ice can.

I have found that by forming a groove in the narrow walls of the can and running from top to bottom of the can, I can not only smooth out any irregularities in said walls, but also reinforce the walls against future buckling, and hence another object of my invention is to provide means for forming grooves in the walls of the can. While my machine is particularly adapted for use on the narrow walls of the can it will be understood that with slight variations in dimensions it could also be used for grooving the wider walls of the can as well.

Still another object of my invention is to

provide a machine which will straighten and groove opposite walls of the can simultaneously.

A further object of my invention is to provide means for forming the groove progressively from one end of the can to the other, so that less effort will be required to operate the machine.

A still further object of my invention is to provide a simple and inexpensive machine for performing the operations outlined above.

With these and other objects in view my invention consists in certain novel features of construction and combinations and arrangements of parts, as will be more fully hereinafter described and pointed out in the claims.

In the accompanying drawings, 75

Fig. 1 is a side elevation of my improved straightening and grooving machine, showing the machine in open position, certain parts being broken away;

Fig. 2 is a side elevation of the machine partly broken away, illustrating the method of straightening and grooving a can, the can being shown in section;

Fig. 3 shows a cross-section taken on the line 3—3 of Fig. 2; and 85

Fig. 4 is a perspective view of a can grooved by my machine.

In general my machine comprises a fixed jaw A, an upper movable jaw B, and an intermediate movable jaw or can carrier C. 90

The fixed jaw A is preferably formed of two channel beams 10, 10, riveted or otherwise secured in relatively spaced relation to a pair of transverse channel irons 11, which serve as feet. A blade 12 is fitted between the members 10 and projects from the upper face of the jaw A, being secured thereto by means of bolts 13. Secured to the upper face of the jaw A, and on opposite sides of the blade 12, are a pair of cheek plates 14.

The upper jaw B is similarly formed of a pair of channel beams 15, between which is fitted a blade 16 secured by bolts 17, the latter serving also to clamp the members 15 together. The blade 16 projects from the lower face of the jaw B, and on opposite sides of the blade, cheek plates 18 are secured to the members 15.

The carrier C serves to carry the cans 110 that are to be grooved, and consists of an upper pair 19 and a lower pair 20 of chan-

nel irons secured to intermediate spacers 21. The channel irons of each pair are spaced apart, as indicated in Fig. 3, to provide a slot 22, into which the blades 12 and 16 may press the metal of the can to form the grooves. It is essential that the carrier C should fit snugly into the cans and particularly against the walls that are to be grooved, and, as different makes of cans are apt to vary slightly in size and taper, the spacers are removably secured to the members 19 and 20, so that they can be readily replaced with others of a different size. It will be understood that the spacers 21 are of progressively different height, to give the carrier C the necessary taper to fit the cans.

As clearly shown in the drawings the carrier jaw C is much shorter than the jaws A and B. Secured to the under face of the jaw C and at the rear end thereof, is a hinge block 23 which is recessed to engage a hinge pin 24 seated on a block 25 carried on the upper face of the fixed jaw A. On the upper face of the jaw C, directly above the block 23, is a hinge block 26, in which is seated a hinge pin 27. Engaging the pin 27 is a hinge block 28 secured to the under face of the jaw B. The jaws are tied together to prevent the hinge blocks from slipping off the hinge pins, by means of tie rods 29 which connect a transverse plate 30 secured to the upper face of jaw B, to a similar transverse plate 31 secured to the bottom of the jaw A. The tie rods are aligned with the hinge pins 24 and 27 when the jaws are in closed position, as indicated in Fig. 2, and the tie rods are sufficiently flexible to permit the jaws B and C to swing to the open position shown in Fig. 1.

The upper flanges of the channel beams 19 and the lower flanges of the beams 20 are extended rearwardly and are curved to form rockers 32 and 33 which bear against the upper face of the jaw A and the lower face of the jaw B, respectively. The channel beams of jaw B extend well to the rear of the hinge pin 27 to provide a counter weight which automatically swings the jaw to open position. As the jaw swings open it engages the rocker 33 causing the jaw C to swing on the hinge pin 24 to a position intermediate between the jaws A and B, as shown in Fig. 1. The lower rocker 32 aids in determining this intermediate position. The rockers are more or less resilient so as to adapt themselves to the angular movements of the jaws. To aid in opening the machine the jaw C is also provided with a counter weight which may consist of a heavy rod 34, secured in any suitable manner to the jaw. If desired a weight 35, indicated in broken lines in Fig. 1, may be secured to the rod 34.

At the forward end of the machine I pro-

vide a link 36 hinged by a pin 37 to the jaw A, and a link 38 hinged by a pin 39 to the jaw B. A bifurcated lever 40 straddles the outer end of the link 38 and is fulcrumed thereto by means of a pin 41. The lever is formed with hooks 42, adapted to be caught under oppositely projecting ends of a pin 43 secured in the outer end of the link 36. On the opposite side of the fulcrum from the hooks 42, the lever 40 is provided with a shank 44.

In operation the jaws B and C are allowed to swing open to the position shown in Fig. 1, and the links 36 and 38 are swung out of the way to the position shown by broken lines; then a can that is to be straightened and grooved is placed on the jaw C. Such a can is shown in section at 45, in Fig. 2. Thereafter the links 36 and 38 are moved to the full line position shown in Fig. 1, and the jaw B is swung down until the hooks 42 can be caught under the pin 43. To provide additional leverage for operating the machine an extension lever 46 is provided, which has a socket into which the shank 44 may be snugly fitted. The extension lever may consist of a piece of pipe. By the use of an extension lever a very powerful leverage is had for drawing the jaw B down and pressing the blades 12 and 16 into the can. Owing to the angular movement of the jaws B and C the blades 12 and 16 do not instantly contact with the can throughout their entire length, but engage near the fulcrum first and as the jaws close the point of contact progresses out toward the front of the machine. By thus forming the groove progressively instead of instantly throughout the whole length of the blades, less power is required to operate the jaws.

The cans are usually formed with a bead 48 at the mouth to stiffen them. The cheek plates 14 and 18 are made of a length to clear this bead and press the metal of the can firmly against the bottom and top, respectively, of the carrier C, so as to form well defined grooves 47. As the grooves are formed in the can the metal of the can is stretched and the buckled portions are smoothed out; the grooves then reinforce the walls of the can and stiffen them against buckling.

When pressure on the lever 46 is released the jaws B and C open by gravity to the position shown in Fig. 1, so that on swinging the links 36 and 38 out of the way the can 45 may be readily drawn off the carrier jaw. If desired one of the grooving blades, preferably the lower one, can be omitted, and the grooving can then be done on one side at a time, thus reducing the amount of power requisite to operate the jaws. This might be found necessary in the case of cans with very heavy walls.

While I have described my invention as

applicable to the straightening and grooving of ice cans it will be evident that my invention could also be used for the straightening and grooving of other types and forms of cans and I wish it to be understood that I do not limit myself to the specific application above described. It will also be understood that while I have described a preferred form of my invention I consider myself at liberty to make various changes in construction without departing from the spirit and scope of my invention as described and defined in the following claims.

I claim:

- 15 1. In a machine of the character described, a relatively fixed jaw, a movable jaw fulcrumed to move toward and from the fixed jaw, a support for a can angularly movable intermediate between and in the plane of 60 said jaws, said support being formed with a slot, and a grooving blade carried by one of said jaws and cooperating with said slot to form a groove in the can.
- 20 2. In a machine of the character described, a relatively fixed jaw, a movable jaw fulcrumed to move toward and from the fixed jaw, a support for a metal can angularly 65 movable intermediate between and in the plane of said jaws, said support being formed with a slot, a grooving blade carried by one of the jaws and cooperating with said slot to 70 form a groove in the can, and cheek plates mounted respectively upon opposite sides of the blade to hold the body of the can against the support during the grooving of the can.
- 25 3. In a machine of the character described, a relatively fixed jaw, a movable jaw fulcrumed to move toward and from the fixed 75 jaw, a support for a can angularly movable intermediate between and in the plane of said jaws, a grooving blade carried by each 80 jaw, the support being provided with slots respectively alined with said blades, cheek plates on opposite sides of each blade, and 85 means for moving the movable jaw toward the fixed jaw, whereby the blades will be moved angularly into engagement with the can to progressively groove the can on opposite sides thereof simultaneously.
- 30 4. In a machine of the character described, a relatively fixed jaw, a movable jaw fulcrumed to move toward and from the fixed 90 jaw, a support for a can angularly movable intermediate between and in the plane of said jaws, a grooving blade carried by each 95 jaw, the support being provided with slots respectively alined with said blades, cheek plates on opposite sides of each blade, and means for moving the movable jaw toward the fixed jaw, whereby the blades will be moved angularly into engagement with the can to progressively groove the can on opposite sides thereof simultaneously.
- 35 5. In a machine of the character described, a relatively fixed jaw, a movable jaw fulcrumed to move toward and from the fixed 100 jaw, a support for a can angularly movable intermediate between and in the plane of said jaws, a grooving blade carried by each 105 jaw, the support being provided with slots respectively alined with said blades, cheek plates on opposite sides of each blade, and means for moving the movable jaw toward the fixed jaw, whereby the blades will be moved angularly into engagement with the can to progressively groove the can on opposite sides thereof simultaneously.

jaw, the support being formed with slots respectively alined with said blades and co-operating therewith to form grooves in the can, means for closing the movable jaw upon the support and the support upon the fixed 60 jaw to form said grooves, a counterweight for opening the movable jaw, and automatic means for moving the support to open position intermediate between the jaws.

5. In a machine of the character described, 65 a relatively fixed jaw, a support for a can fulcrumed on the fixed jaw, a movable jaw fulcrumed on the support, and tie rods alined with said fulcrums and connecting the movable jaw with the fixed jaw.

6. In a machine of the character described, 70 a relatively fixed jaw, a support for a can fulcrumed on the fixed jaw, and a movable jaw fulcrumed on the support, the fixed and the movable jaws having extensions rearwardly from the fulcrums and the support being formed with rearwardly extending rocker arms engaging said extensions and so formed as to maintain the support in an intermediate angular position between the jaws 75 when the movable jaw is swung open on its fulcrum.

7. A machine of the character described, 80 comprising a relatively fixed jaw and a relatively movable jaw, and a carrier jaw 85 mounted to move intermediately between said fixed and movable jaws, said carrier jaw being adjustable to fit cans of different sizes.

8. In a machine of the character described, 90 a relatively fixed jaw, a relatively movable jaw, and a support for a can mounted to move intermediately between said jaws, said support comprising an upper beam and a lower beam, and spacing members between 95 said beams and removably secured to said beams.

9. In a machine of the character described, 100 a relatively fixed jaw, a support for a can fulcrumed on the fixed jaw, a movable jaw fulcrumed on said support, a pair of links connected respectively to the forward end of the jaws, a pin secured to one of the links, and a lever fulcrumed to the other link and adapted to engage said pin, whereby the 105 lever may be operated to close the movable jaw against the support and the support against the fixed jaw.

BERNHARD A. MOHR.
